United States Patent Office.

JOSEPH RYAN, OF ST. LOUIS, MISSOURI.

Letters Patent No. 65,611, dated June 11, 1867.

IMPROVED SCUTTLE-DOOR FOR BUILDINGS, DRY-DOCKS, AND VESSELS.

The Schedule referred to in these Letters Patent and making part of the same.

TO ALL WHOM IT MAY CONCERN:

Be it known that I, JOSEPH RYAN, of the city and county of St. Louis, State of Missouri, have invented a new and improved Scuttle-Door for Vessels, Buildings, Dry-Docks, &c.; and I do hereby declare that the following is a full and exact description thereof, reference being had to the accompanying drawings, and to the letters of reference marked thereon. Of said drawings—

Figure 1 is a general plan, showing the application of my improvements to the deck or floor of a vessel.

Figure 2 is a plan, showing the under side of a deck and the arrangement of a scuttle-door, with lock and water-injection hose.

Figure 3 is a sectional elevation, showing the scuttle-door and its mode of fastening to the deck, roof, or floor, and also the general manner of joining the deck or roof planking.

Figures 4 and 5 show in detail the jointing of the planking on length seams; and

Figure 6 shows in detail the transverse or end seams of the planking.

Firstly, the nature of my invention consists in the application of one or more safety or scuttle-doors to the decks of shipping, dry-docks, &c., or floors or roofs of buildings, arranged to permit an inspection of enclosed spaces, and to permit the application of the usual means for extinguishing fires; said scuttles being, moreover, made water or fluid-tight, and with locks to prevent the entrance of unauthorized persons.

To enable those skilled in this art to make and use my said improvement, I will now proceed to describe its construction and operation; and in this description I will specially describe the application of my said improvement to the decks of vessels intended for use on water, this being the application of said improvements which will be in more general use and of more general benefit; but I do especially state that my said improvements may and do find useful application to buildings generally in the same manner as to vessels on water service.

At such points on the deck A of a vessel, where it would be useful to gain access to parts otherwise inaccessible or inconveniently accessible, I construct the safety-door or scuttle B, usually of some non-corrosive metal, like brass. The scuttle B consists of the frame C and the door D. The parts are so arranged with reference to the surface of the deck A as not to protrude, the deck planking being cut out to receive the frame C, so that their upper surfaces are in the same plane, and the door D resting when closed similarly in the frame C. The joint between the frame C and A I secure in a perfectly water-tight manner. The frame C is secured against A by screw-bolts c passing from the under side of A, and screwing into proper bosses on the lower side of C, as at c', said bolts c being arranged so as in nowise to reach the upper surface of C, so that under all contingencies of wear or injury the upper surface of C above said bolts c shall remain intact, thereby preventing all danger of water leakage at these points. To prevent the bolts c from cutting into the contact surface of A, a washer, c², may be inserted between said surface of A and the head of the bolt. The door D is connected with the frame C by means of proper hinges, substantially as shown. When the door is shut down it is retained securely in its seat in the frame by a lock, E, which may be made of a bolt, e, spring e', said bolt being moved by a key, e², and upon withdrawal of the key being forced out by said spring e', or of any equivalent devices. In the arrangement shown the bolt e enters a proper mortise in the frame C whenever the door is dropped into position without the application of the key; the key, moreover, is used to raise the door. Should the door be heavy, a handle may be conveniently attached to D. The door D is of such size as to permit the passage of a man, or it may be larger, permitting the passage of goods, &c.

Whenever it becomes advisable or necessary to inspect or repair any apartment of a vessel or building, the design here is to permit such inspection or repair by the passage of an operative through said door D. This is of especial importance in ships where certain apartments may foul or become leaky or be otherwise injured, when the same would not be accessible, or not easily accessible, from the main hatches or gangways. To prevent great damage and danger by fires, I have arranged the cap-nut d, closing an opening, d', in D. A boss on the lower surface of D receives the hose d², and this has the nozzle d³. In said nozzle a series of holes permit water to pass out of the nozzle and pass in all directions in the apartment below and surrounding. When, therefore, it becomes necessary to extinguish flames, a connection can be quickly made, (after the nut d has been removed,) the interior surface of d' being arranged with screw-threads to secure the cap-nut d; these may be used to secure a proper nozzle of the supply hose. In this wise the introduction of water for extinguishing fires may be quickly and

effectually made, and at the same time an exclusion of air, which is almost perfect, be attained, thereby greatly lessening the damage and danger from fires in unapproachable apartments. Another mode of introducing a large solid stream of water is indicated by red lines in fig. 3. The supply hose is here simply connected with a bent nozzle, d^1 , (which is so bent as to pass from above through the opening d^1 .) This nozzle can, by manipulating the supply hose, easily be turned so as to throw a stream in all the directions needed.

Having thus fully described my invention, what I claim therein as new, and desire to secure by Letters Patent, is—

The combination and arrangement of a scuttle-door, B, having one or more fire-safety openings d^1 , and conducting and distributing hose or pipes d^2 d^3 d^4 , with decks, roofs, &c., substantially in the manner and for the purposes herein set forth.

JOSEPH RYAN.
